(57) **CLAIM**

The ornamental design for a display screen or portion thereof with a transitional graphical user interface, as shown and described.

DESCRIPTION

FIG. 1 is a first image in a sequence for a display screen or portion thereof with a transitional graphical user interface showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The broken lines showing a display screen or portion thereof, text, symbols, and portions of the graphical user interface illustrate portions of the article, and form no part of the claimed design.

The appearance of the graphical user interface transitions sequentially between the images shown in FIGS. 1-7. The process or period in which one image transitions to another forms no part of the claimed design.

The image shows a wireframe of a mobile application interface. At the top, there is a navigation bar with a back arrow, the text 'Dashboard', and a search bar labeled 'Search Dashboards'.

The main content area is a search results page for 'Restaurant Finder'. The search parameters are: '3 people', '30 June 2015', 'Sushi House', and 'Japanese'. The results are listed in a table:

Restaurant	Address	Phone	Capacity
Sushi House (187)	123 Main St, New York, NY 10001	(212) 555-1234	30
Tokyo Garden (187)	456 Elm St, New York, NY 10002	(212) 555-2345	30
Wasabi Kitchen (187)	789 Oak St, New York, NY 10003	(212) 555-3456	30
Tempura Tei (187)	567 Pine St, New York, NY 10004	(212) 555-4567	30

Below the table, there is a message box with the placeholder 'Type a message...'. A large, semi-transparent search bar is overlaid on the entire page, containing the search parameters and the results table.
